UNITED STATES PATENT OFFICE.

LEWIS D. PARKER, OF HARTFORD, CONNECTICUT, ASSIGNOR TO THE
HARTFORD RUBBER WORKS COMPANY, OF SAME PLACE.

RUBBER FOOT-MAT.

SPECIFICATION forming part of Letters Patent No. 665,370, dated January 1, 1901.

Application filed October 16, 1900. Serial No. 33,231. (No model.)

To all whom it may concern:

Be it known that I, LEWIS D. PARKER, a citizen of the United States of America, residing in Hartford, in the county of Hartford and State of Connecticut, have invented a certain new and useful Improvement in Rubber Foot-Mats, of which the following is a description, reference being had to the accompanying drawings, wherein—

10 Figure 1 is a top or plan view of a corner of a foot-mat embodying the said improvement. Fig. 2 is a view of the part that is shown in Fig. 1 in vertical section on the plane denoted by the dotted line $x-x$. Fig. 15 3 is a top view of the metallic plate and scraper, hereinafter referred to.

The object of the improvement is the production of a rubber foot-mat provided with a metallic scraper.

20 In the accompanying drawings the letter a denotes a foot-mat, of rubber or one of its compounds. It bears on its surface and integral therewith the corrugations a' in diamond form, which serve as "scrapers."

The letter b denotes a metallic plate which is embedded in the body of the mat a in the process of manufacture, it being perforated (see Fig. 3) to make the grasp of the rubber upon the metallic plate b a secure one. From the metallic plate b rises a metallic scraper b' . At each side of that metallic scraper there is a space of the upper surface of the rubber mat left free of the rubber corrugations, an arrangement which gives the metallic scraper more effective action and also serves as a 35 pocket to catch the scrapings.

I claim as my improvement—

A corrugated rubber foot-mat having embedded therein a metallic plate from which a metallic scraper rises above the surface of the rubber foot-mat and provided with a 40 pocket in the mat and about the metallic foot-scraper, all substantially as described and for the purposes set forth.

LEWIS D. PARKER.
